(57) **CLAIM**

The ornamental design for an instrument panel, as shown and described.

DESCRIPTION

FIG. 1 is a perspective view of an instrument panel, showing my new design; The broken lines are for illustrative purposes only and form no part of the claimed design;

FIG. 2 is an enlarged top plan view thereof;

FIG. 3 is an enlarged front plan view thereof;

FIG. 4 is an enlarged bottom plan view thereof;

FIG. 5 is an enlarged right side elevation view thereof, it being understood that the left side is a mirror image thereof; and,

FIG. 6 is a section view taken along line 6—6 in FIG. 3.
